Patented Aug. 15, 1922.

UNITED STATES PATENT OFFICE.

EUGENE B. TAGGART, OF INDIANA, PENNSYLVANIA.

RAIL CLAMP.

1,425,915.

Specification of Letters Patent. Patented Aug. 15, 1922.

Application filed November 16, 1920. Serial No. 424,484.

To all whom it may concern:

Be it known that I, EUGENE B. TAGGART, a citizen of the United States, and resident of Indiana, in the county of Indiana and 5 State of Pennsylvania, have invented a new and useful Improvement in Rail Clamps; and I do hereby declare the following to be a full, clear, and exact description thereof.

My invention relates to rail-clamps or 10 fasteners, and more particularly clamps or fasteners for use in the laying of rails used in coal mines, or other places where comparatively light rails are employed.

The object of my invention is to provide 15 a rail-clamp or fastener of this character which will be simple in construction and effectively clamp or fasten the rail to the tie without the employment of any bolts, nuts, spikes or other devices which are liable 20 to work loose and allow the rail to shift or move, which may result in the derailment of the cars and the trouble and annoyance consequent thereto, and furthermore one which may be easily and quickly unfastened.

25 To these ends my invention comprises the novel features hereinafter set forth.

In the drawing Fig. 1 is a plan view of my improved clamp in clamping position; Fig. 2 is a plan view showing the clamp 30 released; Fig. 3 is a cross-section of the rail with my clamp applied thereto; Fig. 4 is a side view showing the rail clamp in position just before it is forced into position with the clips engaging the flanges of the rail; 35 Fig. 5 is a section on the line 5—5 Fig. 1; Fig. 6 is a plan view of a modified form; and Fig. 7 is an end view of the same.

The numeral 2 designates a suitable tie 40 preferably made of metal in the form of an inverted trough. The tie 2 has the circular opening 3 formed therein to receive the inverted dished member 4, a beading 5 being formed around said opening engaged by the curved flange 6 of said dished member 4.

45 Riveted by the rivet 7, or otherwise secured to the dished member 4, is the clamping plate 8, a washer 7^a being interposed between said plate and the tie 2. This clamping plate 8 is preferably formed of spring 50 steel of the requisite rigidity and resiliency, and said plate is bent over on itself as at 9 and 10 in opposite directions to form the diagonal wings 11 and 12. At the ends of 55 the wings 11 and 12 are formed the clips 13 and 14 which are adapted to engage the

rail flange 15 of the rail 16 at opposite sides thereof.

The clips 13 and 14 normally extend down at an angle to the rail-flanges due to the 60 fact that the wings 11 and 12 are at an angle to the base of the rail, as clearly indicated in Figs. 2 and 4.

Welded to the wing 11, or otherwise secured thereto, or if desired formed integral 65 therewith, is the spring-clip 17 which is adapted to engage the rail-flange at a point opposite to the clip 13. In this way the rail-clamp is held from movement in either direction around its pivotal point. 70

In the operation of clamping a rail by my improved clamp, the clamp is swung around to the position indicated in Fig. 2 and the rail 16 is then laid therein. The clamp is then moved around until the clips 13 and 14 75 come into contact with the edges of the rail-flanges as shown in Fig. 4, with the inner ends of said clips extending above and over said flanges. Force is then applied to bring the clamp into the position shown in 80 Fig. 1, and by this force the clips are gradually sprung until they engage the rail-flanges for their full length. The spring of the metal will act to cause the clips to grip the rail-flanges and hold the clamp 85 securely in place against turning to release the rail. However to further insure the clamp against turning on its pivot when once fixed in clamping position I employ the clip 17 which springs up on the opposite 90 side of the rail to engage the rail-flange opposite the clip 14.

In Figs. 6 and 7 I have shown a modified form of my invention in which the spring-clip 18 is formed by cutting the metal and 95 turning it up to form said clip.

By my invention I provide a rail-clamp which may be permanently attached to the tie so that it cannot become lost or misplaced, and which does not require any 100 bolts, nuts, spikes or other fastening devices which are liable to work loose and allow the rail to shift or move.

The device is simple in construction and not liable to get out of order and does not 105 require any special tools to tighten or release it.

What I claim is:

1. The combination with a tie, of a 110 spring-metal plate pivotally mounted thereon, oppositely extending clips at each end of said plate adapted to engage the rail-

flanges at opposite sides of said rail, said clips normally extending down at an angle to said rail flanges, and the inner ends of said clips projecting above said flanges.

5 2. The combination with a tie, of a spring-metal plate pivotally mounted thereon, said plate being bent to form oppositely extending diagonal wings, inwardly extending clips at the ends of said wings adapted 10 to engage the rail-flanges, said clips normally extending down at an angle to said rail-flanges, and the inner ends of said clips projecting above said flanges.

3. The combination with a tie, of a 15 spring-metal plate pivotally mounted thereon, said plate being bent to form oppositely extending clips at the ends of said wings adapted to engage the rail-flanges, said clips normally extending down at an angle to

said rail-flanges, the inner ends of said clips 20 projecting above said flanges, and a second spring-clip on one of said wings adapted to engage the opposite rail-flange from that engaged by the clip on said wing.

4. The combination of a tie, having 25 a circular opening therein with a downwardly extending beading surrounding said opening, a dished member engaging said opening and having an outwardly turned flange engaging said beading, and a clamp- 30 ing-plate secured to said dished member.

In testimony whereof, I, the said EUGENE B. TAGGART, have hereunto set my hand.

EUGENE B. TAGGART.
